PRESSURE SWITCH

Louis E. Sauer, Sharon, Pa., assignor to Westinghouse Electric Corporation, East Pittsburgh, Pa., a corporation of Pennsylvania

Application November 23, 1954, Serial No. 470,639

3 Claims. (Cl. 200—83)

This invention relates to relays and, in particular, to pressure and/or rate of pressure change responsive relays for effecting the disconnection of a transformer from a power source when a fault occurs within the transformer.

When a fault occurs within the transformer, such as to produce an arc between the transformer windings, a disintegration of the insulating material and oil disposed around the winding takes place. Such arcs, having once started, are likely to continue until the disintegration of the insulation reaches such a point that the current to the winding becomes of sufficient magnitude to trip a line breaker and disconnect the transformer from the power source. However, it is a considerable period of time from the initiation of the fault to that time when the line breaker is tripped. Due to the fact that the arc is permitted to continue during this time interval, considerable damage may be done to the transformer windings. It is, therefore, desirable to disconnect the transformer from the power source during the early stages of the fault regardless of its magnitude.

An object of this invention is to provide a new and improved relay that is responsive to two operating conditions.

Another object of this invention is to provide a pressure responsive relay which effects an operation in response to both a sudden increase in pressure and to a predetermined pressure, but not to gradual increases in pressure.

A further object of this invention is to provide for increasing the speed of response of a pressure responsive relay.

Still another object of this invention is to provide a pressure responsive relay which has a high speed of response and yet a minimum of maintenance.

Another object of this invention is to provide a pressure responsive relay which is so constructed and associated with a transformer tank that normal movement of the transformer tank wall, due to changes in pressure within the tank, has substantially no adverse effect on the operation of the pressure responsive relay.

A more specific object of this invention is to provide for so associating a pivoted arm member having a switch mounted thereon with pressure responsive means and with a stop member that the inertia of the pivoted arm member prevents its movement on sudden pressure changes to thus effect an actuation of the switch, and yet permits bodily movement of the switch in response to gradual changes in pressure until the stop member prevents its further movement and thus permits the pressure responsive means to effect an actuation of the switch.

Other objects of this invention will become apparent from the following description when taken in conjunction with the accompanying drawing, in which:

Fig. 1 is a schematic diagram of a transformer embodying the teachings of this invention;

Fig. 2 is a view partly in section taken along the line II—II of Fig. 1; and

2

Fig. 3 is a detail view of the microswitch shown in Fig. 1 with cover off.

Referring to Fig. 1, this invention is illustrated by reference to a transformer 10. As is customary, the transformer 10 comprises a receptacle or transformer tank 12 within which is disposed a magnetic core member 14 having primary windings 16 and 17 disposed in inductive relationship therewith. In this instance, the transformer tank 12 is of the form-fit type, however, it is to be understood that other types of receptacles or tanks are equally applicable to this invention. In order to electrically insulate the various components such as the core member 14 and the windings 16 and 17 from one another and from the tank 12, a dielectric fluid, such as transformer oil 18, is disposed in the tank 12.

Under normal operating conditions the pressure within the tank 12 may increase gradually due to for instance changes in ambient temperature or changes in the load on the transformer. This effects an increase in the total pressure within the tank 12. However, a fault produces impulse changes in pressure of varying magnitude, but does not materially effect the total pressure within the tank 12.

In accordance with the teachings of this invention, a protective device or pressure responsive relay 20 is provided to effect a deenergization of the transformer 10 when the pressure of the transformer oil 18 suddenly increases, or when the pressure of the transformer oil 18 increases to a predetermined value under normal operating conditions. However, as will be explained more fully hereinafter, the pressure responsive relay 20 does not immediately effect a deenergization of the transformer 10 when gradual increases in the magnitude of the pressure of the transformer oil 18 occur. Thus, the transformer 10 is protected from faults of large or small magnitude and from gradual increases in pressure which continue for a relatively long period of time so as to increase the transformer oil pressure to a predetermined value.

Deenergization of the transformer 10 is effected by a circuit breaker 22 which is responsive to the operation of the pressure responsive relay 20. The circuit breaker 22 is shown schematically and comprises movable and stationary contact members 24 and 26, respectively, a trip mechanism 28, and a handle 29 for effecting a manual resetting of the circuit breaker 22. As shown, the trip mechanism 28 includes a magnetic core member 30, the positioning of which is determined by the energization of an operating coil 32. In order to effect a return of the magnetic core member 30 to its normal position after having been actuated as a result of current flow through the operating coil 32, a compression spring 34 is provided.

Energy for the transformer 10 is received from a power source (not shown) through supply conductors 36 and 38 which are connected to the primary windings 16 through high voltage bushings 40. On the other hand, the secondary winding 17 is connected to a load (not shown) through low voltage bushings 42.

Broadly, the pressure responsive relay 20 comprises pressure responsive means 44 responsive to changes in the pressure of the transformer oil 18, a movable switch 46 normally biased to a predetermined position by gravity, the pressure responsive means 44 being disposed to effect an actuation of the movable switch 46 in response to sudden changes in the pressure of the transformer oil, and effect a bodily movement of the movable switch 46, without actuating the switch 46, in response to gradual changes in the pressure of the transformer oil 18, and a stop member for limiting the bodily movement of the movable switch 46 so that the pressure responsive means 44 can effect an actuation of the movable switch 46.

Specifically, the pressure responsive means 44 com-

prises a metallic Sylphon bellows 50 having a base member 52. The end opposite the base member 52 is suitably secured to a plate member 54 which carries an adjusting nut 55 having a passageway 56 for receiving an actuating member or a switch operating rod 58 which is suitably secured to the base member 52 for movement therewith. As illustrated, the passageway 56 is of such diameter that the interior of the Sylphon bellows 50 is exposed to atmospheric pressure and, thus, owing to a minimum of inertia, quickly responds to a change in the pressure of the transformer oil 18. However, the exterior of the Sylphon bellows 50 is exposed only to the pressure of the transformer oil 18, the transformer tank 12 being sealed off to atmospheric pressure.

In order to bias the Sylphon bellows 50 to its extended position, a compression spring 60 is disposed around the switch operating rod 58 and between the adjusting nut 55 and the base member 52 of the Sylphon bellows 50. In practice, the strength of the compression spring 60 determines the pressure range over which the pressure responsive relay 20 will effectively operate. That is, the higher the expected pressure of the transformer oil 18 at the relay location, the greater must be the resisting force of the compression spring 60. However, in order to adjust for small variations in the magnitude of the static head of oil 18, the adjusting nut 55 is provided. As illustrated, the nut 55 threadedly engages the plate 54 and bears against the end of the compression spring 60. The higher the head of oil 18 the further is the nut 55 screwed into the plate 54. Thus, irrespective of the magnitude of the head of oil 18, the positioning of the rod 58 with respect to the movable switch 46 is maintained.

As illustrated, the movable switch 46 is mounted for movement with a pivoted arm 62 which pivots about a pivot point 64. Also mounted for movement with the pivoted arm 62 is a mass or adjustable nut 65. Specifically, the adjustable nut 65 threadedly engages the end 66 of the pivoted arm 62. Thus, the distance of the nut 65 from the pivot point 64 can be readily varied. In order to prevent movement of the adjustable nut 65 with respect to the pivoted arm 62 once the desired position of the nut 65 has been obtained, a lock nut 68 is provided.

The pivoted arm 62, the movable switch 46, the adjustable nut 65, and the lock nut 66 comprise an unbalanced mass whose inertia can be changed by varying the position of the adjustable nut 65 along the length of the pivoted arm 62. For instance, if the distance between the adjustable nut 65 and the pivot point 64 is decreased, the inertia of the unbalanced mass is likewise decreased, to thereby require a more rapid rate of increase, or a more sudden increase in the pressure of the transformer oil 18, in order to effect an actuation of the movable switch 46. Thus, by adjusting the nut 65, the value of rate of increase of pressure at which the movable switch 46 is actuated under sudden increases in transformer oil pressure can be varied. It is to be noted that due to the above-described structure, the operating pin 69 of the movable switch 46 remains in contact with the end of the rod 58 irrespective of the pressure of the oil 18 surrounding the bellows 44.

The reason that the switch operating rod 58 is able to effect an actuation of the movable switch 46 when sudden increases in the transformer oil pressure occur is that the inertia of the unbalanced mass, which includes the movable switch 46, is greater than the switch operating force needed to effect an actuation of the movable switch 46. On gradual increases in the transformer oil pressure, the switch operating force, as effected by the switch operating rod 58, is not of sufficient magnitude to effect an actuation of the movable switch 46 and as a result, the movable switch 46 is bodily moved until its further movement is prevented by the stop member 48. When further movement is prevented, the movable switch

46 is actuated by the switch operating rod 58, as will be explained more fully hereinafter.

In this instance, the movable switch 46, as illustrated in more detail in Fig. 3, is a microswitch and comprises a stationary contact member 70, a movable contact member 72 carried by a snap acting leaf spring 74 which in normal operation biases the movable contact member 72 to the open position with respect to the stationary contact member 70, and the operating pin 69 which actuates the snap acting leaf spring 74 in response to the outward movement of the switch operating rod 58.

Referring again to the stop member 48, the stop member 48 comprises an L-shaped bracket 78, one end of which is suitably secured to the plate member 54, an adjustable screw 80 carried by the bracket 78, and a lock nut 82 provided to prevent movement of the adjustable screw 80 with respect to the bracket 78 once the screw 80 has been properly adjusted. The position of the end of the screw 80 with respect to the movable switch 46 determines at what total transformer oil pressure the movable switch 46 will be actuated. For instance, the closer the end of the screw 80 to the movable switch 46, the lower will be the pressure of the transformer oil 18 at which the movable switch 46 is actuated.

The operation of the apparatus illustrated in Fig. 1 will now be described. Assuming the pressure of the transformer oil 18 suddenly increases, then a pressure wave front will strike the base member 52 of the Sylphon bellows 50, to thereby effect a movement of the switch operating rod 58 to the left, as illustrated. When the switch operating rod 58 is suddenly actuated to the left, it effects an actuation of the operating pin 69 of the movable switch 46, to thereby effect a snap action of the leaf spring 74, to thus bring the movable contact member 72 into electrical contact with the stationary contact member 70.

When the movable contact member 72 of the movable switch 46 is in electrical contact with the stationary contact member 70, an electrical circuit is completed to the operating coil 32 of the trip mechanism 28. The energization of the operating coil 32 effects a movement of the magnetic core member 30 to the left, as illustrated, to thereby effect an opening of the circuit breaker 22, to thus deenergize the transformer 10. When the fault or other condition bringing about the sudden increase in the pressure in the transformer oil 18 is relieved, the compression spring 60 restores the Sylphon bellows 50 to its normal position. Of course, in order to reenergize the transformer 10, the handle 29 must be actuated upward to thereby close the circuit breaker 22.

Assuming the pressure of the transformer oil 18 gradually increases, then the switch operating rod 58 is gradually actuated towards the left, as illustrated. However, the force exerted on the operating pin 69 of the movable switch 46 is not of sufficient value to effect a snap action of the leaf spring 74. Therefore, a bodily movement of the movable switch 46 is effected which continues as the transformer oil pressure gradually increases until finally the movable switch 46 engages the end of the screw 80. When the movable switch 46 engages the end of the screw 80, further movement of the switch 46 is prevented and thus, on further movement of the switch operating rod 58 to the left, the movable contact member 72 is brought into electrical engagement with the stationary contact member 70. When the contact members 70 and 72 are brought into electrical engagement, the transformer 10 is deenergized in the same manner as hereinbefore described.

The apparatus embodying the teachings of the invention has several advantages. For instance, even though a pressure wave front effects a slight movement of the transformer tank wall associated with the pressure responsive device 20 still owing to the inertia of the unbalanced mass, which includes the movable switch 46, there is substantially no movement of the switch 46.

Such being the case, the speed of response of the pressure responsive means 20 is maintained at a high value. In addition, the pressure responsive means 20 comprises few components which can be readily manufactured and assembled. Further, the pressure responsive means 20 is readily adaptable to transformers of different power ratings.

Since certain changes may be made in the above described apparatus and different embodiments of the invention may be made without departing from the spirit and scope thereof, it is intended that all matter contained in the foregoing description or shown in the accompanying drawing shall be interpreted as illustrative and not in a limiting sense.

I claim as my invention:

1. In combination, a receptacle containing a fluid under pressure, an arm pivoted about a predetermined pivot point, a switch having operating means for effecting an actuation of the switch, the switch being mounted on the pivoted arm for movement therewith, a mass also mounted on the pivoted arm for movement therewith, said mass being adjustable so that its distance from the pivot point can be varied, pressure responsive means including an actuating member disposed to engage and effect an actuation of said switch operating means, said actuating member being responsive to the pressure of the fluid for actuating the switch in response to sudden changes in fluid pressure and for effecting bodily movement of the pivoted arm and switch, without actuating the switch, in response to gradual changes in the fluid pressure, and means for limiting the movement of the switch so that the said actuating member can effect an actuation of the switch when the fluid pressure reaches a predetermined value.

2. In combination, a receptacle containing a fluid under pressure, an arm pivoted about a predetermined pivot point and having threads on the end thereof opposite the pivot point, a nut disposed on the threaded end of the pivoted arm, the nut being adjustable so that its distance from the pivot point can be varied, a switch having operating means for effecting an actuation of the switch, the

switch being mounted on the pivoted arm for movement therewith, pressure responsive means including an actuating member disposed to engage and effect an actuation of said switch operating means, said actuating member being responsive to the pressure of the fluid for actuating the switch in response to sudden changes in fluid pressure and for effecting bodily movement of the pivoted arm and switch, without actuating the switch, in response to gradual changes in the fluid pressure, and means for limiting the movement of the switch so that the said actuating member can effect an actuation of the switch when the fluid pressure reaches a predetermined value.

3. In combination, a receptacle containing a fluid under pressure, an arm pivoted about a predetermined pivot point and having threads on the end thereof opposite the pivot point, a nut disposed on the threaded end of the pivoted arm, the nut being adjustable so that its distance from the pivot point can be varied, a switch having operating means for effecting an actuation of the switch, the switch being mounted on the pivoted arm for movement therewith, pressure responsive means including a Sylphon bellows having a base member and an actuating member carried by the base member and disposed to engage and effect an actuation of said switch operating means, said actuating member being responsive to the pressure of the fluid for actuating the switch in response to sudden changes in fluid pressure and for effecting bodily movement of the pivoted arm and switch, without actuating the switch, in response to gradual changes in the fluid pressure, and means for limiting the movement of the switch so that the said actuating member can effect an actuation of the switch when the fluid pressure reaches a predetermined value.
